UNITED STATES PATENT OFFICE.

HANS J. ANDERSEN, OF HOMER, NEBRASKA.

INCUBATOR.

1,070,315.

Specification of Letters Patent.

Patented Aug. 12, 1913.

Application filed June 10, 1912. Serial No. 702,826.

To all whom it may concern:

Be it known that I, HANS J. ANDERSEN, a citizen of the United States, residing at Homer, in the county of Dakota and State 5 of Nebraska, have invented certain new and useful Improvements in Incubators; and I do declare the following to be a full, clear, and exact description of the invention, such as will enable others skilled in the art to 10 which it appertains to make and use the same.

This invention relates to improvements in incubators.

The object of the invention is to provide 15 an incubator with improved ventilating means for the egg chamber which is simple in construction and efficient in operation.

With this and other objects in view the invention consists of certain novel features 20 of construction, and the combination and arrangement of parts as will be more fully described and claimed.

In the accompanying drawings; Figure 1 is a perspective view of my improved incubator; Fig. 2 is a vertical sectional view 25 on the line 2—2 of Fig. 4; Fig. 3 is a similar view taken at right angles to Fig. 2 and on the line 3—3 of Fig. 4; Fig. 4 is a horizontal sectional view on the line 4—4 of Fig. 2.

Referring more particularly to the drawings, 1 denotes the body portion of my improved incubator, said body comprising an outer casing 2, an intermediate casing 3 and an inner casing 4 formed of wood and spaced 30 a suitable distance apart. Between the outer and intermediate casings are arranged layers 5 of corrugated straw board or paper and between said layers of corrugated paper is arranged a packing 6 of hair felt. Between 35 the inner and intermediate casings are arranged layers 7 of corrugated straw board between which is formed an air space 8. Within the inner casing 4 is arranged a lining 9 formed of sheet metal.

In one side of the body 1 is formed an 45 opening which is normally closed by a door 10 having therein a glass panel 11 through which the interior of the incubator may be observed. The space inclosed by the galvanized sheet metal lining 9 forms the egg chamber 12 and in the lower portion of said chamber are arranged the egg trays 13, said trays being preferably constructed of galvanized sheet metal and are supported upon

a sheet metal support 14 constructed as 55 shown.

In one side of the incubator and communicating at its inner end with the air space 8 is an air inlet pipe 15 whereby air is admitted to the space 8. 60

Arranged in the inner side of the incubator and connecting the space 8 with the upper portion of the egg chamber is an air inlet passage 16 through which the air from the space 8 enters the upper portion of the 65 egg chamber. The air thus entering the egg chamber circulates therein and passes therefrom through a discharge pipe 17 arranged in the lower portion of the incubator and extending up through the air space 8 and 70 out through the top of the incubator as shown. By thus arranging the air inlet and discharge pipes the egg chamber is perfectly ventilated without being cooled.

Secured to one side of the incubator is a 75 heating apparatus comprising a water heating tank or boiler 18 which is inclosed in an outer casing 19 between which and said tank is arranged a suitable packing whereby the heat is prevented from radiating from 80 the tank 18. Arranged through the center of the heating tank or boiler 18 is a heat conducting tube 20 the upper and lower ends of which extend through the upper and lower ends of the casing 19 as shown 85 and with the lower end of the tube 20 is engaged the upper end of the heat conducting flue or chimney 21 of the lamp or other heating device (not shown). Connected with the upper end of the tank 18 is 90 a filling tube 22 while with the lower end of the tank is connected a faucet 23 whereby the water may be drawn from the tank when desired. To the upper portion of the tank or boiler 18 is connected a hot water 95 discharge pipe 24 the inner end of which is connected with a tapering heating coil 25 arranged in the upper portion of the egg chamber and which comprises a narrow loop shaped inner or centrally disposed portion 25^a the ends of which are turned outwardly and extend around the sides of the upper portion of the egg compartment as shown at 25^b, the coil gradually increased in size from the inner looped portion 25^a 100 to the discharge portion thereof as indicated. The discharge or inlet pipe 24 is connected to the looped inner portion of

the coil while to the center of the outer portion is connected a return pipe 26 to the lower portion of the tank or boiler 18. By thus arranging the discharging and return pipes 24 a circulation of hot water is maintained through the coil 25 to heat the egg chamber, the pipes 24 and 26 are detachably secured to the boiler 18 by unions or other suitable couplings as shown.

10 Supported above the heat conducting tube 20 and adapted to be moved toward or from the upper end thereof is a heat regulating damper 27, said damper being suspended from the outer end of a supporting and operating lever 28 arranged above the incubator and pivotally connected near its inner end to a supporting bracket 29, said lever having on its inner end an adjustable counter balancing weight 30 whereby the lever is balanced to support the damper 27 at its proper normal position above the upper end of the heat conducting tube 20.

Arranged in the upper portion of the incubator is a lever actuating yoke or frame 31 comprising parallel vertically disposed rods 32 which are slidably engaged with passages formed through the top of the incubator and are connected together at their upper ends by a cross head 33 and at their lower ends by a cross bar or plate 34. Arranged through the center of the cross head 33 is a lever engaging bolt 35 the lower end of which is engaged with the inner end of the damper supporting lever 28 and on which above and below the cross head 33 are arranged adjusting nuts 36 whereby the frame or yoke 31 is adjusted with respect to the lever 28.

Secured to the lower end of a hanger 37 40 is a thermostat 38 which is preferably formed of a plurality of expansible disks and which is engaged with the cross bar or plate 34 of the yoke or frame 31 whereby when said thermostat expands from the heat in the egg chamber a downward pressure will be exerted upon the yoke, thus drawing the latter downwardly into the incubator and causing the upper end thereof to depress the inner end of the lever 28 and to 45 lift the outer end thereof, thus raising the damper 27 to a greater or less distance above the upper end of the heat conducting tube thereby permitting more or less heat to escape from the tube. By thus permitting the heat to escape from the heat conducting tube 20 the water in the tank or boiler 18 and in the heating pipes and coil is allowed to cool to a greater or less extent, thus reducing the temperature in the 50 egg chamber.

In order to prevent any possibility of the chamber from becoming overheated, I provide a supplemental temperature regulating mechanism whereby should the temperature 55 of the egg chamber increase beyond a pre-

determined point outside air will be automatically admitted to the lower portion of the egg chamber, thus reducing the temperature therein. The supplemental temperature regulating mechanism referred to 70 comprises a pair of horizontally disposed levers 39 and 40 which are pivotally connected at their inner ends to an operating frame 41 arranged beneath and adapted to be brought up into engagement with the plate 75 or bar 34 forming the lower end of the yoke 31. The levers 39 and 40 are fulcrumed near their inner ends or connection with the frame 41 to the lower ends of supporting rods 42, the upper ends of which project through the top of the incubator and are threaded to receive adjusting nuts 43 by means of which the rods are adjusted to bring the frame 41 into engagement with the cross bar or plate 34 of the yoke. The outer end of the lever 40 is operatively connected with a slide valve 44 which is adapted to open and close an air inlet port 45 formed in the adjacent side of the incubator and communicating with the air space 8 90 therein as clearly shown in Fig. 3 of the drawing. The outer end of the lever 40 is tapered to form a pointer or indicating finger 46 which is adapted to point to a scale indicating degrees of temperature and 95 arranged on a suitably supported plate 47 secured to the inner portion of the door 10 whereby the same may be readily observed through the glass panel 11 of the latter.

In preparing the incubator for use the egg chamber is permitted to become heated to 103 degrees which is the temperature at which the heat in the chamber is to be maintained. This temperature may be ascertained by a thermometer temporarily placed in the egg chamber. In obtaining the desired temperature in the egg chamber the thermostat 38 will be expanded to a certain extent, thus lowering the yoke 31 100 as hereinbefore described. After the required temperature has been obtained and the thermostat thus expanded the nuts 43 on the supporting rods 42 are adjusted in the proper direction for bringing the frame 115 41 up into engagement with the lower side of the cross bar or plate 34 of the yoke. When the frame 41 has thus been adjusted the pointer on the outer end of the lever 40 will be brought opposite to the 103 degree mark of the temperature scale of the plate 46 and the valve 44 connected to the outer end of the lever 39 will be in such position that the upward movement of the same by the lever 39 will open the air port 120 45, and permit the outside air to enter the lower portion of the egg chamber. With the parts thus arranged it will be readily seen that should the temperature of the egg chamber increase beyond 103 degrees that 125 130

a further extension of the thermostat 38 will occur which will force the yoke 34 and frame 41 downwardly. The downward movement of the frame 41 will rock the levers 39 and 40 thus causing the outer end of the lever 39 to open the valve 44 to a greater or less extent and will cause the lever 40 to indicate on the temperature scale the increased temperature of the egg chamber. This downward movement of the yoke 31 will also rock the damper supporting lever 28 causing the latter to lift the damper 27 to a greater or less distance above the upper end of the heating tube 20 there-
by permitting the heat to escape and the water in the boiler and heating coil to cool, which action together with the admission of the additional supply of outside air to the lower portion of the egg chamber will cool the latter or reduce the temperature therein to a normal state whereupon the thermostat will contract and permit the outer ends of the levers 39 and 40 to lower, and close the valve 44 and cause the pointer 45 to indicate the reduction of the temperature on the scale of degrees as will be readily understood. By thus constructing and arranging the heat controlling mechanism the temperature of the egg chamber will be automatically controlled thus obviating the necessity of watching the incubator to prevent the overheating of the egg chamber.

By providing the incubator with a metal lining which incloses the egg chamber the moisture expelled from the eggs or otherwise accumulating in the egg chamber is prevented from evaporating or from being absorbed, which action occurs in incubators having wood linings or wood inclosed egg chambers. The moisture thus retained by improved form of incubator keeps the heated air of the egg chamber in a moist condition necessary for the successful hatching of the eggs in the incubator.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is:

1. In an incubator, an egg chamber, a heating apparatus therefor, a lever provided with a damper for controlling said apparatus, a yoke slidably mounted in the top of said chamber, a bolt extending through the outer cross head of said yoke and engaging said damper lever, means for adjusting said yoke relatively to said lever, a hanger depending in said egg chamber, a thermostat secured to said hanger and engaged with the inner cross head of said yoke, a frame arranged in said egg chamber beneath said yoke and adapted to engage the inner cross head thereof, a horizontal lever fulcrumed on said frame, a supporting rod connected with said lever and extending through the top of the chamber and provided with adjusting means, a valve connected with said lever for opening and closing said air inlet simultaneously with the opening and closing of the damper.

2. In an incubator, an egg chamber, a heating apparatus therefor, a lever provided with a damper for controlling said apparatus, a yoke slidably mounted in the top of said chamber, a bolt extending through the outer cross head of said yoke and engaging said damper lever, means for adjusting said yoke relatively to said lever, a hanger depending in said egg chamber, a thermostat secured to said hanger and engaged with the inner cross head of said yoke, a frame arranged in said egg chamber beneath said yoke and adapted to engage the inner cross head thereof, a horizontal lever fulcrumed on said frame, a supporting rod connected with said lever and extending through the top of the chamber and provided with adjusting means, a valve connected with said lever for opening and closing said air inlet simultaneously with the opening and closing of the damper, and means connected with said valve actuating lever for indicating the temperature of the chamber.

In testimony whereof I have hereunto set my hand in presence of two subscribing witnesses.

HANS J. ANDERSEN.
